DOUBLE-SIDED BRUSH

Kurt Krusche, Frankfurt am Main, and Hubert Zimmermann, Mannheim, Germany, assignors to Allstar Verbruchsguter G.m.b.H. & Co. K.G., Frankfurt, Germany

Filed Oct. 5, 1970, Ser. No. 25,330

Claims priority, application Germany June 15, 1970

Term of patent 14 years

Int. Cl. D4—02

U.S. Cl. D86—13

FIG. 1

FIG. 2

FIG. 3

FIG. 4

FIG. 1 is a front plan view of a double-sided brush showing my new design;

FIG. 2 is a side elevational view looking from either the right or left of FIG. 1;

FIG. 3 is a top end view looking from the top of FIG. 1; and

FIG. 4 is a bottom end view looking from the bottom of FIG. 1, seen from the handle end of the brush.

We claim:

The ornamental design for a double-sided brush, substantially as shown and described.
